UNITED STATES PATENT OFFICE.

CHARLES E. BUELL, OF SPRINGFIELD, MASSACHUSETTS, ASSIGNOR OF ONE-THIRD TO WILKING B. COOLEY, OF EASTON, PENNSYLVANIA.

VELOCIPED.

SPECIFICATION forming part of Letters Patent No. 331,276, dated December 1, 1885.

Application filed October 16, 1884. Serial No. 145,649. (No model.)

To all whom it may concern:

Be it known that I, CHARLES E. BUELL, of the city of Springfield, county of Hampden, State of Massachusetts, have invented Im-5 improvements in Propelling Vehicles, of which the following is a specification.

My invention relates to propelling tricycles and other similar vehicles.

My invention consists, primarily, in the 10 combination, with a tricycle, of a holder removably attached thereto, a motor or engine adapted to be made operative by compressed air to propel said vehicle, and means for connecting said holder to said motor that are 15 provided with mechanism for controlling the flow of air between said holder and said motor, the whole arranged substantially as hereinafter described.

My invention further consists in certain 20 combinations and sub-combinations, to be hereinafter described.

Figure 1 shows a tricycle in front elevation arranged according to my invention. Fig. 2 is a side elevation of the same. Fig. 3 is a 25 view of a detailed part of my invention. Fig. 4 is a view in perspective of a tricycle arranged according to my invention.

In the accompanying drawings the same 30 letters and figures refer to corresponding parts in each.

Referring to Figs. 1 and 2, A is a tricycle of any preferred construction, having a holder, B, attached thereto in such a manner as to be readily removed therefrom, for purposes which 35 will be hereinafter mentioned. A rotary motor or engine, C, is shown rigidly secured to the frame-work of the tricycle, and connected to revolve the axle *a* when in motion. The motor C has a throttle-valve, with lever *h* for 40 controlling a supply of air to the motor when the valve *V* has been turned to allow the air to pass from the charged holder B through the tube D to the motor C. The tube D is adapted to be connected and disconnected with 45 the valve *V*, for obvious purposes. By having the holder B of steel, or otherwise made light and strong, and having it removably attached to the vehicle, several charged holders may be successively placed upon the vehicle 50 and successively connected to the motor by

the tube D, which is common to the several holders. The valve *V*, being made a part of the holder B, serves to retain the charge of air in its respective holder until it is required to be used. A lantern, L, is shown suspended 55 below the exhaust *b* of the motor C in such a manner as to light the path of the vehicle, and at the same time to keep the exhaust warmed with obvious advantages.

Fig. 3 shows the frame *f* of a tricycle made 60 hollow and adapted to hold a supply of compressed air for propelling the motor C C, which is a double oscillating engine provided with a throttle-valve and handle *h*. The valve *V* serves for connecting the frame *f* to a compressing apparatus to be charged, and to connect the frame *f* with a holder that is charged, and the contents of which is to serve as an auxiliary supply of air when the charge in the frame *f* becomes exhausted.

Fig. 4 represents a tricycle having an oscillating engine, C, adapted to propel the vehicle by operating the treadle-crank T T. The holder B is shown removably attached to the vehicle and connected to the frame *f* in a manner to serve as an auxiliary air-supply. The chamber B is provided with a valve, *V*, and the frame *f* is also provided with a valve, *V*, the valves on the chamber and frame being connected by a tube, D.

When it is desired to use the contents of the holder B to operate the engine and to hold the compressed air stored in the frame *f* as a reserve supply, the valve *V* being closed, the holder B should be connected to the portion 85 of the frame at *X* by a conducting-tube like that shown in Fig. 1 for connecting the holder to the engine. By thus connecting it the supply of air to the engine will be under control of the throttle-valve with lever *h*. By this 90 means holders may be used successively upon a tricycle, and a reserve supply for cases of emergency may be carried without adding to the weight or bulk of the vehicle. Tricycles arranged in this manner may be worked by 95 power of compressed air, or by the treadles T T, in which latter case the piston-rod *p* may be detached from the crank *d*.

When the holder B is suitably constructed of steel, it may be charged with a supply of 100

air sufficient to propel a tricycle several miles, and as a number of charged holders may be successively used with a single tricycle, owners of tricycles may be supplied with several 5 charged holders, which may be replenished from time to time.

I contemplate employing a safety-valve (not shown) of compact form, connected to the tricycle in such a manner that its use may be 10 common to several holders used successively. Any preferred form of motor or engine adapted to be operated by compressed air may be used in place of those shown.

Although I have confined my description to 15 the use of compressed air, as I prefer its use to that of gas or hydrocarbon distillates, I may use gas compressed in receptacles that are removably attached, and herein described as "holders," and as a motor employ a gas- 20 engine of the type known as the "Shipman," "Brayton," or "Otto" engine, without departing from my invention.

What I claim is—

1. The combination, with a tricycle, of the 25 holder B, provided with a valve, V, and removably attached to said tricycle, an engine mounted upon said tricycle and adapted to propel said tricycle, and means for connecting said holder B to supply said engine, substantially as described.

2. The combination, with a tricycle, of the 30 holder B, removably attached thereto, an engine mounted on said tricycle, and means for connecting said holder B to supply said engine that are provided at two points with devices for controlling the flow of air from said holder B to said engine.

3. The combination, with a tricycle, of the removably-attached holder B, an engine for propelling said tricycle, and a throttle-valve 40 provided with a lever for controlling the air-supply to said engine.

4. The combination, with a vehicle having a hollow frame charged with compressed air, of the holder B, removably attached to said 45 vehicle and portable therewith, an engine mounted on said vehicle, and suitable means for connecting said holder B and said frame successively to said engine to supply it with air for propelling said vehicle.

5. The combination, with a vehicle having a hollow frame charged with compressed air, of the holder B, removably attached to said vehicle and portable therewith, an engine mounted on said vehicle, and suitable means 55 for connecting said holder B and said frame successively to said engine to supply it with air for propelling said vehicle, and added means for controlling the flow of air to said engine.

6. The combination, with a vehicle, of the 60 holder B, provided with a valve, V, removably attached to said vehicle, an engine mounted upon said vehicle and adapted to propel said vehicle, means for connecting said holder B to supply said engine, and independent devices for propelling said vehicle by foot-power, substantially as described.

CHARLES E. BUELL.
